UNITED STATES PATENT OFFICE

2,610,373

MIXER-MULLER

Jules T. Parisi, Chicago, Ill.

Application April 26, 1950, Serial No. 158,266

1 Claim. (Cl. 22—89)

1

The present invention relates to apparatus for conditioning granular or pulverulent material and more particularly to an apparatus for conditioning molding sand of the type used in foundries.

In modern foundry practice molding materials, commonly called sand, consist primarily of sand which may be either new or used sand to which certain other materials are added, such as binding and peeling materials or agents. These materials must be thoroughly intermixed with and uniformly distributed in the sand if uniform results are to be achieved in casting. The apparatus of the present invention embodies improved continuously operating means for preparing molding sand for use.

One object of the present invention is to provide a new and improved apparatus for conditioning molding sand for use which operates continuously as distinguished from the so-called batch type conditioning apparatus and which is capable of conditioning sand in one pass through the apparatus.

Another object of the invention is to provide a new and improved apparatus for conditioning molding sand which subjects the sand to both mulling and mechanical mixing operations and which delivers the sand thoroughly fluffed and aerated in condition for use.

A further object of the invention is to provide apparatus of the type specified in the preceding objects which incorporates improved sand mulling apparatus.

A still further object of the invention is to provide new and improved apparatus for conditioning molding sand which may readily be adapted and regulated for varying the amount of conditioning to which the sand is subjected.

Another object of the invention is to provide new and improved apparatus for conditioning molding sand which may be used in conjunction with an endless conveyor that transports sand from a place of storage to a place of use and which apparatus conditions the sand while it is being so transported.

A further object of the invention is to provide new and improved apparatus for conditioning molding sand in which the generation of heat is greatly reduced without impairing the effectiveness of the apparatus.

A still further object of the invention is to provide new and improved apparatus for conditioning molding sand which is capable of much greater output than known apparatus of comparable cost, and which produces a molding sand of uniform texture that is cooler and has greater

permeability and flowability than the sands produced by conventional mulling apparatus.

A more general object of the invention is to provide new and improved apparatus for conditioning molding sand which may be constructed at relatively low cost and is easy to install and maintain but which nevertheless may be operated for extended periods without requiring adjustment, repair or cleaning.

These and other objects, advantages and capabilities of the invention will become apparent from the following description wherein reference is had to the accompanying drawings, in which:

Fig. 1 is a side elevational view of the improved apparatus of the present invention;

Fig. 2 is a top plan view of the sand conditioning apparatus disclosed in Fig. 1;

Fig. 3 is a view similar to Fig. 1 on an enlarged scale with parts of the apparatus broken away and parts in section more clearly to disclose the construction thereof;

Fig. 4 is a fragmentary perspective view on an enlarged scale of the cutters which form part of the sand conditioning apparatus of the present invention;

Fig. 5 is a top plan view of a portion of the apparatus of the present invention on the same scale as Fig. 3 and with portions of the apparatus broken away more clearly to disclose the structure thereof;

Fig. 6 is a vertical transverse sectional view on an enlarged scale taken on the line 6—6 of Fig. 3;

Fig. 7 is a fragmentary perspective view on an enlarged scale of the muller forming part of the sand conditioning apparatus of the present invention; and

Fig. 8 is a fragmentary elevational view showing a chain drive for the muller of the present invention.

Referring to the drawings, it will be seen that the improved sand conditioning apparatus of the present invention may be installed along a section of endless conveyor such as a standard endless belt having an upper reach 12 and a lower reach 14. In describing the invention it will be assumed in reference to the drawings that the upper reach 12 of the conveyor moves from left to right (Figs. 1 to 3). It will further be assumed that the left hand end of the conveyor is located

adjacent a place of storage for the sand to be conditioned such as a hopper (not shown) from which the conveyor is supplied, or it may be supplied from a place of storage by another conveyor belt (not shown). The sand to be conditioned may be either raw or spent molding sand,

or a mixture of the two. In any event certain materials such as binding and peeling agents are added to the sand proper either before or as it is supplied to the upper reach 12 of the conveyor to improve its qualities, and the apparatus of the present invention is designed, among other things, thoroughly to mix these agents with the sand.

As best seen in Figs. 1 to 3, the novel sand conditioning apparatus of the present invention comprises a plurality of separate stages or stations, each of which includes an agitator or cutter stage 16 comprising a pair of rotatable cutters 18 of duplicate construction and a muller stage 20 including a supporting roller 22 below the upper reach 12 of the conveyor and a muller roll or wheel 24 above the upper reach of the conveyor. Since these stages are of duplicate construction, only one will be described in detail. In Figs. 1 to 3 the cutters 18 and muller rolls 24 are arranged for an endless conveyor whose upper reach 12 is traveling from left to right as seen in those views. Three stages are shown in Figs. 1 and 2 but the number of these stages may be increased or decreased as required properly to condition a particular kind of molding sand or a sand for a particular use.

Support for the sand conditioning elements is provided by a main frame of structural irons comprising a plurality of vertically extending angle irons 26 interconnected by a plurality of longitudinally extending horizontal angle members 28, 30, 32 and 34, and a plurality of transversely extending horizontal angle iron members 36. These frame members are joined to each other by welding, bolting or any other suitable means. This main frame extends longitudinally of the endless conveyor and side and top wall plates 38 and 40, respectively, extending the length of the main frame are secured thereto to form a housing enclosing the cutters 18 and at least a portion of the muller wheels 24. However, the top wall 40 and the side walls 38 at the muller stages are provided with apertures for a purpose to be described. End wall plates 42 may be provided to close the opposite ends of the housing formed by the top and side wall plates. This housing is somewhat narrower than the endless conveyor and the lower edges of the side wall plate 38 extend into close proximity to the top side of the upper reach 12 of the conveyor as indicated at 44 (Fig. 6) so as to tend to prevent material on the conveyor from spilling off the sides thereof.

Preferably doors 46 (Figs. 1 and 4) are hinged to openings 48 in the side wall plates 38 opposite the cutters 18 so that access may readily be had to these cutters. Openings 50 in the side walls 38 to the rear of the muller rolls 24 do not necessarily have to be closed because the sand is being compacted on the conveyor at the muller stages and thus will not be likely to be scattered through the openings 50.

Circulation of air through the housing for the purpose of cooling the sand on the conveyor and to provide ventilation may be had through branch pipes 52 communicating at one end with the upper end of the housing for the cutters and mullers over the cutters 18 at each stage and at the other end with an exhaust duct 54 connected to a suitable source of suction.

The cutters 18 in each stage preferably each comprise three metal discs 56 fixedly mounted in spaced relation upon a supporting and drive shaft 58 (Figs. 5 and 6) which discs support two

sets of blades 60 in angularly disposed relation to each other. These blades each preferably comprise a relatively heavy band or ribbon helically curved from end to end thereof. At their opposite ends the blades are received in radially extending notches or slots 62 in adjacent discs 56 and they may be fixed thereto by welding or other means. The cutter shafts 58 are rotatably supported adjacent opposite ends in suitable pillow blocks 64 fixed to the longitudinally extending horizontal frame members 28 so as to support the periphery of the cutters spaced approximately $\frac{1}{16}$ of an inch above the top side of the upper reach 12 of the conveyor.

Preferably as best seen in Fig. 2 the cutters 18 in each stage are provided with a separate source of power such as a conventional electric motor 66. This motor drives the cutters 18 through a V-belt 68 passing over a pulley 70 on the armature shaft of the motor and a pulley 72 on the shaft 58 of one of the cutters. The second cutter in each stage is driven from the shaft of the first by means of a V-belt 74 (Fig. 5) which passes over duplicate pulleys 76 fixed on the cutter shafts 58 for the two cutters in each stage 16. Thus the two cutters in each stage are driven in the same direction and at the same speed. The periphery of these cutters preferably move in the same direction as the direction of linear movement of the upper reach 12 of the conveyor on that side of the cutters which is being carried toward the conveyor. The cutters therefore rotate in a counterclockwise direction as seen in Fig. 3. It has been found that best results are obtained in most cases when the peripheral speed of the cutters 18 is approximately eight times the linear speed of the conveyor although other speeds may be used if circumstances make it desirable.

Each of the muller rolls 24 comprises a hollow cylindrical drum 78 (Fig. 6) preferably of stainless steel having enclosing end walls 80 to which circular flanges 82 on hubs 84 are bolted or otherwise fixedly secured. The hubs 84 are fixed upon drive and supporting shafts 86 by means of set screws 88 in the hubs 84.

The muller roll shafts 86 are rotatably supported adjacent opposite ends in suitable bearings 90 carried adjacent the free ends of a pair of rocker arms 92 which form part of an independent frame on the main frame for carrying the muller wheels 24 and the drive means therefor. In addition to the rockers 92, this frame which may be made from structural irons such as channel iron members includes a pair of uprights 94 welded or otherwise suitably secured adjacent their lower ends to the free ends of the rocker arms 92 and a cross piece 96 connecting the upper ends of these vertical frame members 94. A tubular spacer 98 may be provided between the anchored ends of the rockers 92 to rigidify the entire muller roll frame.

A connection between the main frame and muller roll frame to adapt the latter and the muller roll for rocking movement relative to the main frame may be provided, for example, by oppositely extending trunnions 100 journaled in suitable pillow blocks 102 fixed upon longitudinal frame members 30. A shaft extending transversely of the rockers through the spacer 98 might be used for the same purpose. The uprights 94 in the muller roll frame extend through the apertures previously described in the top wall 40 of the housing, and the apertures 50 in the side wall plates 38 allow for rocking movement.

of the muller wheel frame relative to these side walls.

Adjacent their free ends the rocker arms 92 are provided with stops in the form of cap screws 104 which are adapted to engage upon cooperating stops 106 fixed to certain of the vertically extending members 26 in the main frame to limit movement of the rocker arms 92, and muller roll 24 toward the upper reach 12 of the conveyor. The distance the muller roll is supported above the conveyor by these cooperating stops can be varied by turning the adjusting screws 104 one way or the other and then locking the same at a position of adjustment by means of lock nuts 108. A scraper 110 is provided for each muller roll 24 which scraper may be secured to the muller roll framework in any suitable manner (Figs. 3 and 7).

Like the cutters 18, each of the muller rolls 24 has its own source of power which may comprise a conventional electric motor 112 mounted on the cross member 96 in the muller roll frame (Fig. 6). Through a gear reduction unit enclosed in a housing 114 this motor drives a relatively small sprocket 116 drivingly connected by means of a sprocket chain 118 to a relatively large sprocket 120 fixed on the muller roll shaft 86. An idler sprocket 122 carried by a rockably mounted arm 124 which may be locked at various positions of adjustment maintains the sprocket chain 118 taut. Preferably a sufficient reduction in speed is provided by the motor driven gear reduction and the sprockets 116 and 120 so that the peripheral velocity of the muller roll 24 is substantially the same as the linear velocity of the upper reach of the conveyor. The muller roll preferably rotates in the same direction as the cutters, namely, counterclockwise as seen in Fig. 3.

By reason of this mounting of the motor 112 on the muller roll frame, it weights the muller roll frame and the muller roll 24. If desired or necessary additional weights (not shown) may be placed on the cross frame member 96 to hold the muller roll 24 against the sand on the conveyor. Additional weight may also be supplied by providing the muller roll 24 with a filling opening 126 through which sand or liquid may be supplied to the interior of the roll to thus weight the same the amount desired. This opening is closed by a suitable screw threaded cap or plug 128.

Subjacent support for the upper reach 12 of the conveyor to relieve strain thereon during mulling and to improve the mulling action of the muller roll 24 is provided by the supporting roller 22 which is supported below the conveyor and is freely rotatable on an axis extending transversely of the conveyor in a plane extending substantially vertically through the axis of the muller roll 24. Roller 22, which may be of conventional construction, has trunnions 130 (Fig. 6) at opposite ends thereof rotatable in suitable pillow blocks 132 supported on longitudinally extending channels 134 in the main frame by means of pedestals or brackets 136. Subjacent support for the upper reach 12 of the conveyor to prevent sagging is also provided by a plurality of conventional supporting rollers 138 rotatably supported in suitable brackets or standards 140 carried by the longitudinal channel members 134. Preferably one of these rollers 138 is located at a point intermediate the two cutters 18 in each cutter stage 16 as indicated in Fig. 3.

Subjacent support for the lower reach 14 of the conveyor may be provided by a plate 142

(Fig. 6) extending from end to end of the main frame between and secured to the lower flanges on the opposed longitudinal channel members 134 or by a series of cross strips or bars supported by these channels and disposed at regularly spaced intervals longitudinally thereof.

The efficiency of operation of the improved mixer-muller of the present invention is increased appreciably by providing directional shovels or plows 144 (Figs. 2 and 5) and dividers 146 between the muller rolls 24 and the cutters 18 adjacent thereto in the direction of forward movement of the conveyor. The shovels 144 may be made from a relatively heavy plate attached at one end to any suitable rigid support such as the inner side of the side wall plates 38 with their lower edges in close proximity to the upper reach 12 of the conveyor. These plates are inclined inwardly so that they extend inwardly of the lateral edges of the conveyor. Sand is therefore stripped from these edges of the conveyor and is directed or plowed toward the center thereof. Each divider 146 may consist of a triangular shaped metal plate and the dividers are supported above the conveyor from any suitable fixed part of the main frame or housing at an intermediate point transversely of the conveyor. They are thus in a position to strip sand from the center of the conveyor and urge it laterally outwardly.

It is also to be noted that shovels 148 (Fig. 2) inclined inwardly of the conveyor are provided after each of the cutter stages 16. These shovels 148 may be similar to the shovels 144 previously mentioned and may be mounted in the same way.

Briefly to describe the operation of the improved mixer-muller, the unconditioned molding sand along with the additional ingredients necessary to form a finished molding material or sand are supplied to the left hand end of the conveyor (Figs. 1 to 3) as previously explained in a layer which may be from one to three inches thick. As the material on the conveyor is carried past the relatively rapidly rotating cutters 18 in the first cutter stage 16, it is thoroughly agitated, thus tending to reduce any lumps therein and to mix the several ingredients thoroughly and at the same time aerate and fluff the material. Furthermore, due to the helical curvature of the blades 60 in the cutters 18 the material on the conveyor is plowed toward the center of the conveyor. This and the fact that the housing plates 38 enclose the cutters and extend into close proximity to the top side of the upper reach 12 of the conveyor prevent the material from being scattered from the conveyor during mixing. Any material which by chance happens to remain near the edges of the conveyor as it is moved past the shovels 148 by the conveyor is plowed inwardly of the edges of the conveyor.

Material is then moved by the conveyor under the muller roll 24 and is thoroughly mulled thereby during the course of which it is spread across the conveyor and compacted into a layer of substantially even thickness. From the muller roll 24 the sand is carried past the dividers 146 and shovels 144 located ahead of the succeeding cutter 18. The combined effect of the shovels 144 and divider 146 is to strip the compacted material from the edges and the center of the conveyor and to windrow it into rows extending longitudinally of the conveyor and spaced outwardly of the center line thereof. Thus the shovels and the divider commences the breaking up of the layer of sand packed on the conveyor by the muller 24. From the shovels 144 and divider 146

the sand is moved to the succeeding cutter stage 16 and the process described above is repeated.

In order that the sand shall be in condition for use when it leaves the last mixer-muller stage in the conditioning apparatus, a cutter stage 150 (Figs. 1 and 2) similar to the cutter stages 16 is provided following the last muller stage 20. Cutters 152, similar in construction and operation to the cutters 18 previously described are provided in this cutter stage 150. For this reason the sand leaving this cutter stage is thoroughly fluffed and aerated to thus cool the same. It therefore is ready for use, and to the extreme right of the portion of the conveyor shown in Figs. 1 and 2 means may be provided for removing the prepared molding sand at a station or stations where it is to be used, or it may be conveyed to a place of storage.

By virtue of the cooperative action of the mixers and mullers molding sand operated upon by the apparatus of the present invention not only is lump-free and more permeable but also is more flowable and appreciably cooler than sand conditioned by the ordinary batch type muller. As a matter of fact, ventilation for cooling purposes is hardly necessary.

The improved conditioning apparatus described herein may be operated continuously because it is not necessary to stop the same for loading and unloading. The entire operation is therefore expedited and a mixer-muller of the type described herein is capable of an output at least double that of a batch type muller of comparable cost. In addition, since the loading and unloading operations incident to the use of a batch type muller are eliminated in the use of the present mixer-muller, there is less wastage and fewer attendants are required to operate the conditioner.

Another advantage of the mixer-muller described herein is the fact that in many instances it may readily be installed along existing conveyor lines without requiring extensive rearrangement or modification thereof, thus reducing the cost of installation. It is also to be noted that the present apparatus may be fabricated almost entirely from standard structural irons or other standard parts and therefore its cost of manufacture is relatively low. By virtue of their construction the various parts of the apparatus tend to be self cleaning and have a long life. Maintenance after initial adjustment of the apparatus therefore is negligible because it consists mainly of the lubrication of the bearings in the various pillow blocks.

It will be observed that additional stages may readily be added to the apparatus if required by the state of the material which is being conditioned, or the amount of conditioning to which it is desired to subject the material. Thus the apparatus can be organized so that the material is completely conditioned in one pass. Furthermore, since the mixers and mullers have individual sources of power, one or more of the stages in a conditioning apparatus may be readily cut out if that becomes desirable. Moreover the apparatus of the present invention is also adaptable for use with conventional batch type equipment where conditioning additional to that provided by the conventional equipment is desired.

Although it is contemplated that the sand being conditioned shall be subjected to the action of

both the cutters and mullers, in some instances or with particular sands a sufficient conditioning may be achieved by merely subjecting the sand to the operation of the muller wheels or the cutters and such operation can readily be had in view of the fact that each of the muller and each of the cutter stages has an individual source of power. This also allows less than all of the cutter stages or muller stages to be placed in operation when the operation of all is not necessary.

While preferred embodiments of the invention have been shown and described, it will be apparent that numerous variations and modifications thereof may be made without departing from the underlying principles of the invention. It is desired, therefore, by the following claim to include within the scope of the invention all such variations and modifications by which substantially the results of the invention may be obtained through the use of substantially the same or equivalent means.

I claim:

A conditioner for granular or pulverulent material having a driven conveyor belt for carrying said material along the upper reach thereof through the conditioner, means for supporting the movement of said belt including a plurality of subjacent support rollers spaced apart beneath said reach, a mixer for said material comprising a pair of rotating cutters having helically curved blades successively carried into close proximity to the upper reach, said pair of blades being arranged above the said belt in position along said reach and adjacent to but between subjacent support rollers, whereby the belt between said support rollers will yield when pressed downward by the blades engaging said material thereon, means drivingly connected with said cutters adapted to rotate the same so that the peripheral speed thereof is substantially greater than the belt speed, and in the same direction at the bottom of the cutters whereby said cutters will cut into said material and throw the same into the air to mix and aerate the same as the material moves along said conveyor, a plurality of walls on the conditioner arranged to enclose the mixer, a mixer roll positioned to operate on the material after it has been agitated by said cutters, a motor geared to said muller roll to drive the same, said motor being mounted in association with said muller roll so as to weight the roll additionally, said roll and motor being freely movable together toward said upper reach for holding the muller roll against the material.
